DESIGN FOR AN AQUARIUM ORNAMENT

Albert Greenberg, New York, N. Y.

Application November 18, 1942, Serial No. 108,817

Term of patent 3½ years

To all whom it may concern:

Be it known that I, Albert Greenberg, a citizen of the United States of America, residing in New York city, county of Kings, and State of New York, have invented a new, original, and ornamental Design for an Aquarium Ornament, of which the following is a specification, reference being had to the accompanying drawing, forming part thereof, wherein,

Figure 1 is a front perspective view of an aquarium ornament showing my new design.

Figure 2 is a rear elevational view thereof.

I claim:

The ornamental design for an aquarium ornament, substantially as shown.

ALBERT GREENBERG.
